UNITED STATES PATENT OFFICE.

HERMAN R. SMITH, OF BROOKLYN, AND PAUL D. CASE, OF PELHAM MANOR, NEW YORK, ASSIGNORS TO CHARLES R. GOW COMPANY, OF BOSTON, MASSACHUSETTS, A CORPORATION OF MASSACHUSETTS.

HOISTING APPARATUS.

Application filed November 19, 1923. Serial No. 675,563.

This invention relates to hoisting apparatus and its chief object is to provide apparatus of simple and inexpensive construction, which can be readily transported from place to place.

5 A further object is to provide a hoisting apparatus, actuated by compressed air, which is under manual control at all time during operation but which is automatically controlled in such manner as to prevent accidents due to 10 over-running. To these and other ends the invention consists in the novel features and combinations hereinafter described.

Of the various forms in which the invention can be embodied we have selected for illustration and description herein a construction designed particularly for use in hoisting earth from excavations made for concrete foundation-piers, piles, columns, and the like, but it is to be understood that the invention is not 20 limited to such use but can be employed to advantage for numerous other purposes.

The embodiment just mentioned is illustrated in the accompanying drawings, in which

25 Fig. 1 is a side view of the hoisting apparatus, with the upper part in section on line 1—1 of Fig. 3.

Fig. 2 is a detail side view of the upper part of the apparatus, showing the brake-mechanism omitted from Fig. 1.

Fig. 3 is a detail elevation from the left of Fig. 2.

Fig. 4 is a detail view, somewhat diagrammatic in character, showing the valve mechanism and brake mechanism.

30 Fig. 4^a is a detail side view showing a modification.

Fig. 5 is a detail section of part of the brake cylinder.

40 Figs. 6, 7, 8, 9, 10, 11, 12, 13 and 14 are diagrammatic views illustrating various operative positions of the hoisting apparatus and of the valve mechanism by which its operation is controlled.

45 In the apparatus shown, the various operative parts are mounted on a frame in the form of a tripod composed of legs 10, 11, 12, detachably connected at the top in any convenient and suitable way, as by means of a bolt 13. The legs 11 and 12 are of the telescoping type, as indicated, so that they can be

readily shortened or lengthened to accommodate the structure to uneven ground. In the drawings the apparatus is shown arranged over a pit 14 from which excavated material 55 is to be hoisted.

Leg 10 is composed of two members (in the present instance channel irons) as indicated in Fig. 3, provided at the top with bearings for the shaft 15, on which the hoisting drum 16 60 and the driving pinion 17 are fixed. The latter is rotated, and with it the shaft and drum, by a rack 18 reciprocated by a piston rod 19 connected to the piston 20 in the fluid-pressure cylinder 21. The rack is kept in mesh with the pinion by a roller 22 mounted in a bracket 23, Figs. 1 and 2, and is protected by a U-shaped guard 24. The shaft 15 also carries a brake drum 25, Figs. 2, 3 and 4, encircled by a flexible brake band 26, one end of which 65 is fixed and the other connected to the piston 27 of a fluid-pressure brake cylinder 28 mounted on leg 10.

The admission and exhaust of compressed air (or other fluid) to and from the hoisting 75 cylinder 21 and brake cylinder 28 are controlled by suitable valve mechanism, in the present instance a pair of three-way valves 30, 31 connected to each other and to the cylinders, and to the source of compressed air, 80 by suitable piping. Valve 30 is connected to the upper end of the two cylinders by pipes 32, 33, to valve 31 by pipe 34, and to the source of compressed air represented by pipe 35; while valve 31 is connected to the lower 85 end of the hoisting cylinder by a pipe 36. The brake piston 27 is raised, to release the brake, by a spring 27^a, and above the piston the brake cylinder is provided with a vent 38, Fig. 4, for slow escape of air under certain conditions, as explained hereinafter. This vent is preferably formed in a hollow 90 plug 39, Fig. 5, screwed into the cylinder so that another having a larger or smaller opening can be readily substituted when necessary 95 or desirable.

The hoisting receptacle or bucket 40 is releasably suspended, as by means of a hook 41, on the cable or line 42, which winds on the drum 16.

100 In the modified form of driving mechanism shown in Fig. 4^a the rack and pinion are re-

placed by a cable 52 connected to the piston rod 19, and a small actuating drum 53 on which the cable is wound, so that as the rod is retracted the drum 53 and the shaft 15 carrying the hoisting drum 16 will be rotated.

The operation of the apparatus will be readily understood by reference to Figs. 6 to 14, inclusive.

Assuming that the bucket is to be hoisted from the excavation (see Fig. 6), the valves are turned to the positions shown in Fig. 7, valve 30 connecting the air supply pipe 35 to pipe 32 and blocking pipe 33, and valve 31 connecting pipe 36 to exhaust pipe 43 and blocking pipe 34. Compressed air now enters the upper end of the hoisting cylinder and retracts the rack 18, thereby rotating the drum 16 and winding the line 42 thereon. At the same time air exhausts from the lower end of the cylinder through pipes 36 and 43. As the bucket approaches or reaches the unloading position the valves are turned to the positions shown in Fig. 8. Pipes 32, 34 and 36 are thus closed and air supply pipe 35 is connected to pipe 33, through which air is delivered to the brake cylinder, thereby applying the brake and arresting the hoisting drum, the air below the brake piston escaping through a suitable vent, not shown. The bucket is now pulled over to the side and the valves are turned to the positions shown in Fig. 10, in which the two ends of the hoisting cylinder are connected through pipes 32, 34 and 36, and the air to the brake cylinder shut off. The air previously admitted to the latter now exhausts slowly through the vent 38 (Fig. 4), permitting the spring 27^a, Fig. 4, to ease off the brake and allow the loaded bucket to descend slowly to the side of the pit, as in Fig. 9. The bucket having been emptied or a previously emptied bucket substituted, the lower valve 31 is turned to the position shown in Fig. 12 (valve 30 remaining as in Fig. 10). The lower end of the hoisting cylinder is thus connected to exhaust pipe 43, whereupon the expansion of the compressed air trapped in the upper part of the cylinder, above the piston, retracts the rack and raises the empty bucket off the ground and allows it to swing back over the excavation, as in Fig. 11. Leaving valve 30 as it was, valve 31 is turned to the position shown in Figs. 14 and 10, thus restoring the condition illustrated in the latter figure, in which the two ends of the cylinder are connected. The empty bucket then descends as in Fig. 13, the air from the upper end of the cylinder merely flowing to the other end. The workman in the pit having loaded the bucket or substituted a previously loaded bucket, the cycle described is repeated.

To prevent accidents due to failure to manipulate the valves at the proper time as the bucket is rising, which might result in jamming the bucket into the top of the tripod,

an automatic stop-mechanism is provided, by which movement of the bucket above a pre-determined position will shut off the air from the hoisting cylinder and apply the brake. The preferred mechanism for the purpose comprises a ring or eye 45, Figs. 1 and 4, suspended by a cable 46 and yieldingly connected to the handle 47 of valve 30 (Fig. 4) by means of a spring 48 and chain 49, the latter running through a tubular guide 50. The hoist line 42 runs through the ring 45 and at a suitable point is provided with an adjustable clip 51 too large to pass through the ring.

Assuming that in Fig. 1 the valves are in the positions shown in Fig. 7, the bucket is then rising, and if the operator should fail to throw the upper valve to the position shown in Fig. 8 the bucket would continue to rise and might be jammed between the hoisting drum and the top of the tripod. Before that can happen, however, the clip 51 meets the ring 45 and raises the latter, first stretching spring 48 somewhat and then drawing chain 49 through the guide 50, thereby rocking valve 30 over to the position shown in Fig. 4, in which the air from pipe 35 is shut off from the hoisting cylinder and delivered through pipe 33 to the brake cylinder. Slight additional upward movement of the bucket, due to expansion of the air trapped in the hoisting cylinder before the brake takes hold, is permitted by the yield of spring 48, but in any case the bucket is arrested before it reaches a dangerous position. It will of course be understood that in practise the length of the chain 49 and the position of the guide 50 are so related as to leave sufficient slack to permit turning the valve clockwise, by hand, to the positions shown in Figs. 8 and 10.

The construction herein illustrated and described gives good results but the invention can be embodied in other forms without departure from its spirit as defined by the following claims.

We claim:

1. In a hoisting apparatus, in combination, a supporting structure, a hoisting drum carried thereby, a pinion to rotate the drum, a rack meshing with the pinion to rotate the same, fluid pressure mechanism to reciprocate the rack, fluid pressure brake mechanism associated with the hoisting drum, and manually operable valve mechanism common to said fluid pressure mechanisms to control the same.

2. In a hoisting apparatus, in combination, a supporting structure, a mechanism carried thereby for hoisting a load, having an actuating pinion, a reciprocating rack meshing with the pinion to rotate the same, a fluid pressure hoisting cylinder having a reciprocating piston connected with the rack to actuate the same, brake mechanism cooperating with the hoisting drum, a fluid pressure brake cylinder having a reciprocating piston connected with

the brake mechanism to actuate the same, and means for controlling the supply and exhaust of fluid pressure, comprising a valve connected with the brake cylinder and with one 5 end of the hoisting cylinder, and a valve connected with the first mentioned valve and with the other end of the hoisting cylinder.

3. In a hoisting apparatus, in combination, a supporting structure, a mechanism carried 10 thereby for hoisting a load, having an actuating pinion, a reciprocating rack meshing with the pinion to rotate the same, a fluid pressure hoisting cylinder having a reciprocating piston connected with the rack to actuate the

15 same, brake mechanism cooperating with the hoisting drum, a fluid pressure brake cylinder having a reciprocating piston connected with the brake mechanism to actuate the same, and means for controlling the supply and exhaust 20 of fluid pressure, comprising a pair of manually operable three-way valves connected with each other and with said cylinders.

4. In a hoisting apparatus, in combination, a supporting structure, a mechanism carried 25 thereby for hoisting a load, having an actuating pinion, a reciprocating rack meshing with the pinion to rotate the same, a fluid pressure hoisting cylinder having a reciprocating piston connected with the rack to actuate the 30 same, brake mechanism cooperating with the hoisting drum, a fluid pressure brake cylinder

having a reciprocating piston connected with the brake mechanism to actuate the same, means for controlling the supply and exhaust of fluid pressure, comprising a pair of manually operable three-way valves connected with each other and with said cylinders, and load-actuated mechanism for operating said controlling means to arrest the load when the latter passes a predetermined position in 35 its travel.

5. In a hoisting apparatus, in combination, a tripod adapted to be positioned over an excavation, a drum for hoisting a load, mounted in the upper part of the tripod, a pinion associated with the drum to rotate the same, a reciprocating rack meshing with the pinion to rotate the same, a fluid pressure cylinder having a piston to reciprocate the rack, brake mechanism associated with the hoisting drum, 40 a fluid pressure cylinder having a piston connected with the brake mechanism to actuate the same, manually operable fluid pressure controlling means for said cylinders, and mechanism actuated by movement of the load 45 past a predetermined position to actuate said controlling means and thereby arrest the load.

In testimony whereof we hereto affix our signatures.
